US00D443597S

(12) **United States Design Patent** (10) Patent No.: **US D443,597 S**
Coleman (45) Date of Patent: ** Jun. 12, 2001

(54) **COMPOSITE DESKTOP FOR A COMPUTER DISPLAY SCREEN**

(75) Inventor: **Patricia J. Coleman**, Montara, CA (US)

(73) Assignee: **Apple Computer, Inc.**, Cupertino, CA (US)

(**) Term: **14 Years**

(21) Appl. No.: **29/087,506**

(22) Filed: **May 4, 1998**

Related U.S. Application Data

(62) Division of application No. 29/038,514, filed on May 5, 1995, now abandoned.

(51) **LOC (7) Cl.** **14-02**

(52) **U.S. Cl.** **D14/114.2**
